UNITED STATES PATENT OFFICE.

FLOYD SHANNON, OF WELLSBURG, WEST VIRGINIA.

ENVELOP-SEAL.

971,316.

Specification of Letters Patent. Patented Sept. 27, 1910.

Application filed February 9, 1910. Serial No. 542,883.

To all whom it may concern:

Be it known that I, FLOYD SHANNON, a citizen of the United States, residing at Wellsburg, in the county of Brooke, State 5 of West Virginia, have invented certain new and useful Improvements in Envelop-Seals; and I do hereby declare the following to be a full, clear, and exact description of the invention, such as will enable others skilled 10 in the art to which it appertains to make and use the same.

This invention relates to envelop seals of that general class designed to secure the closing flap to the body of the envelop so 15 that the contents of the envelop can not be tampered with by unauthorized persons without mutilating the envelop.

The object of this invention is to provide an envelop seal simpler in construction than 20 similar devices of its kind and which may be applied to any ordinary envelop without unduly mutilating the same.

The invention consists of a single piece of wire bent anchor shape, the flukes of the 25 anchor being provided with novel means for holding them normally spread apart as will hereinafter be more fully described and claimed.

For a more detailed description of the invention reference may be had to the accompanying drawing in which—

Figure 1 is a view in elevation of the reverse side of an envelop equipped with my improved seal. Fig. 2 is a view in elevation 35 of an envelop with portions of the front side broken away to disclose the seal. Fig. 3 is a cross-sectional view taken on the line 3—3 Fig. 2. Fig. 4 is a detail perspective view of the seal.

Referring now to the drawing the numeral 8 designates an envelop having a closing flap 9, both of the usual and well-known kind.

The seal comprising the subject matter of 45 this invention consists of a single length of wire looped upon itself adjacent one end as shown at 10 and thence extended at substantially right angles to this loop to form a straight shank 11, the free end of which is 50 split for a portion of its length to provide a pair of resilient fingers 12 which latter are bent back along the shank in the nature of anchor flukes. Each finger 12 is provided on its inner side with an eye 13 formed by 55 splitting the finger or otherwise which en-

gages the shank and operates to normally hold the finger spaced from the shank.

By referring to the drawing it will be seen that the resilient fingers 12 extending from the extreme end of the shank permit of 60 the shank being punched through the envelop flap when inserting the seal, thus obviating the necessity of manufacturing the envelop flap or envelop body with slits or similar openings to receive the shank. 65

In applying the seal to an envelop the resilient fingers 12 are inserted through the reverse side of the envelop flap 9 until the transverse loop 10 comes in contact with the inner side thereof, the seal then being rotated so that the flap of the envelop is 70 closed when the fingers 12 are inserted through the envelop body until the free ends of the fingers have cleared the opening formed in the envelop body by the insertion 75 of the fingers when the fingers will immediately assume the position shown in Fig. 2 and prevent the withdrawal of the seal. It will be seen that when the seal is in operative position the flap can not be raised 80 without causing the seal to be drawn upward toward the flap which operation will force the fingers to mutilate the envelop adjacent the opening therein as long as this raising movement of the seal is continued. 85 It is obvious that the contents of the envelop can not be tampered with without leaving conspicuous traces as evidence of such tampering.

From the foregoing description taken in 90 connection with the accompanying drawing, it is thought that the construction and operation of my invention will be easily understood without a more extended explanation, it being understood that various 95 changes may be made in the minor details of construction within the scope of the appended claim.

I claim—

An envelop seal consisting of a shank having a flap engaging head at one end, and a plurality of envelop body engaging fingers at the other end diverging from the extreme end of said shank toward said head. 100

In testimony whereof, I affix my signature, in presence of two witnesses.

FLOYD SHANNON.
